UNITED STATES PATENT OFFICE.

WILLIAM NEWBY, OF YOUNGSTOWN, OHIO.

PROCESS OF OPENING SHEET AND TIN-PLATE PACKS.

Application filed August 27, 1920. Serial No. 406,437.

To all whom it may concern:

Be it known that I, WILLIAM NEWBY, a citizen of the United States, residing at Youngstown, in the county of Mahoning and State of Ohio, have invented new and useful Improvements in Processes of Opening Sheet and Tin-Plate Packs, of which the following is a specification.

The present invention relates to a process 10 of opening sheet and tin plate packs by means of crimping the pack and then flattening out the crimps or corrugations, and has for its object, to more thoroughly render the pack apart, and at the same time to 15 more thoroughly flatten the sheets which make up the pack. The accompanying drawing illustrates the methods by which these objects are obtained, and in said annexed drawings:—

Fig. 1 shows the usual process of opening sheet and tin plate packs by crimping and flattening the same; Fig. 2 shows the use of flattening rolls at an angle; Fig. 3 shows the use of crimping rolls at an angle through 25 the pack; Fig. 4 shows the use of flattening rolls arranged to be used with packs crimped as shown in Fig. 3; Fig. 5 is a sectional view through a crimped pack in which the pack and crimps are illustrated in full size and 30 the pitch or distance between corrugations is shown as that which has been found necessary in order to obtain a thorough breaking apart of the sheets; Fig. 6 is a plan view of a crimped pack drawn to the same proportions as in Fig. 5, but on a reduced scale; Fig. 7 shows a section through a crimped pack on a plane at right angles to the crimps therein, as indicated by the line 7—7, Fig. 6, the pack being shown in position between 35 flattening rolls, the axes of which are parallel to such line 7—7; and Fig. 8 is a section through such crimped pack, the plane of the section being indicated by the line 8—8, Fig. 6, which lies approximately at the same 40 angle as do the axes of the flattening rolls in my present improved process.

In the usual process, as shown in Fig. 1, the corrugations or crimps 1 and 2 are formed straight across the pack, and the 45 pack is adapted to travel directly from the crimping rolls 3 to the flattening rolls 4. The flattening rolls are parallel to the crimping rolls and then parallel to the corrugations, and the effect of this is to cause 50 the pack to pitch or weave as it goes through the flattening rolls, and then to leave the

rolls with bends corresponding to the crimps. This is undesirable and the pack does not receive the required amount of flattening to cause the sheets to break away from each other.

In my improved process the pack after it has been crimped or corrugated in the manner shown in Fig. 1, is passed through flattening rolls 5 which are mounted at an angle 65 to the corrugations or crimps as best shown in Fig. 2, so that the rolls will span two or more of the corrugations thereby obtaining the maximum flattening effect and the maximum tendency to completely break the 70 sheets apart.

This same effect may be obtained by passing the pack 6 through crimping rolls 3, which are placed at an angle to the pack and then passing the crimp pack through 75 flattening rolls 5, placed directly across the pack as shown in Fig. 4. Here again the flattening rolls will span two or more of the crimps or corrugations in the pack so that the pack will really be flattened and will not 80 weave through the rolls as often done in the usual method, as illustrated in Fig. 1.

It will be understood that packs of tin plate and like material are made up from two sheets of No. 16 gage steel to about 85 twelve sheets of No. 30 gage steel, which makes the packs about one-eighth of an inch thick. In the reheating and rolling of these packs, the sheets become more or less welded together, sometimes only to such a slight extent that each individual sheet may be gripped at one corner by a pair of tongs and stripped off without much effort, but other packs become welded together to such an extent that the sheets will tear apart or 90 break before leaving each other. It has been found by actual test that to make these sheets break away from each other by crimping or corrugating and then flattening the 95 packs, that the crimps must be made deep and not too wide apart. It is, furthermore, important that the sheets be thereafter sufficiently flattened out; otherwise they require either to be separately rolled smooth or else sold at a reduced price.

Where a pack is crimped with the crimps running all the way across the pack of the size shown in Fig. 5 of the drawing, it is impossible to flatten down such crimps by running them through a pair of flattening 110 rolls in the ordinary way, since the result will be that the crimps become buckled or

doubled and the value of the pack thus completely destroyed. However, where the crimps in such pack are formed at an angle such that when the pack is passed through 5 the flattening rolls, the crimps will spread out sidewise from the center towards the ends of the rolls, the pack may be flattened down with a minimum of buckling or tearing, while at the same time a maximum 10 separation of sheets is obtained.

The action just described will be better understood by a comparison of Figs. 7 and 15 8 of the drawing. It will be noted that the width of the strips on the roll contact line are considerably wider in Fig. 8, where the roll lies at a slight angle to the crimps, than in Fig. 7, where the rolls are disposed at a right angle to such crimps. In other words, the pitch of the crimps where rolled out as 20 in Fig. 7 is equal only to the distance C on Fig. 6, while the pitch of the crimps where rolled out as in Fig. 8 is equal to the distance D on Fig. 6.

Other modes of applying the principle of 25 my invention may be employed instead of the one explained, change being made as regards the method herein disclosed, provided the step or steps stated by any of the following claims or the equivalent of such stated 30 step or steps be employed.

I therefore particularly point out and distinctly claim as my invention:—

1. In a method of opening sheet and tin plate packs, the steps which consist in forming the pack with a series of parallel crimps 35 or corrugations disposed at an angle less than a right angle to the ends of such pack, and then passing such pack through a pair of flattening rolls set at an angle less than a right angle to such crimps. 40

2. The method of opening sheet tin plate packs consisting of passing them through a pair of crimping rolls and then passing them through a pair of flattening rolls placed at an angle less than a right angle to the crimps 45 whereby the rolls will span two or more of the crimps but not all of the crimps in the pack.

3. In a method of opening sheet and tin plate packs, the steps which consist in passing the pack through a pair of crimping rolls disposed to crimp such pack at an angle less than a right angle relatively to the ends 50 of such pack, and then passing such pack through a pair of flattening rolls set at an angle less than a right angle to such crimps. 55
